UNITED STATES PATENT OFFICE.

JOHN S. MILLER, OF TRURO, NOVA SCOTIA, CANADA.

FENCE-POST.

1,235,830.

Specification of Letters Patent. Patented Aug. 7, 1917.

Application filed July 11, 1916. Serial No. 108,663.

To all whom it may concern:

Be it known that I, JOHN S. MILLER, a subject of the King of England, residing at Truro, in the county of Colchester, in 5 the Province of Nova Scotia and Dominion of Canada, have invented a new and useful Improvement in Fence-Posts, of which the following is a specification.

My invention relates to posts which are 10 secured generally by having a lower portion embedded in the earth, but is applicable to posts held on the surface by sills or otherwise, and used in the construction of ordinary wire fence, and the object of 15 my invention is, to provide facilities for attaching, securely holding in position and detaching the fence wires.

I attain these objects by the material and mechanism described and illustrated in the 20 accompanying description and drawings, in which,—

Figure 1 is a front view showing a post and attachments essential to my invention. Fig. 2, is an edge view of Fig. 1. Fig. 3 25 is a vertical face view of an angle iron which serves to hold the fence wires and post cap in position. Fig. 4 is a section of Fig. 3. Fig. 5 is an enlarged section of Fig. 1 on wire c. c. Fig. 6 is an enlarged view of a 30 portion of Fig. 1 showing the wire groove and the relation of the angle b. thereto. Fig. 7 is an enlarged central vertical section of the post cap.

Similar letters refer to similar parts 35 throughout the several views.

The post Fig. 1 is of concrete, reinforced or otherwise, the part *a* adapted for insertion in the earth, the exposed part having an approximate 90 degrees vertical groove 40 *b* extending from the ground to top of post for the purpose of partially receiving the angle iron *b* (Fig. 1). *j* are horizontal grooves formed in the front of the post for the purpose of receiving the fence wires 45 *c c c*. *f* is a staple embedded in the concrete near the ground adapted to engage in the notches *g* in the angle iron *b*. *a* is a light metal ornamental cap fitted to the top of the post and projecting down over 50 the angle iron *b* a sufficient distance to allow the projection *d* to engage with the notches *e e* on the angle iron *b*.

The method of operating the device is as follows: Set the post in position, place the

fence wires in the grooves *j*, then place the 55 angle iron *b* in position with the notches *g* engaging the staple *f* and press the top end inward slightly bending the fence wires in the movement until the cap will pass down over the angle and the projection *d* will 60 engage with the notches *e e*. The resilience in the fence wires keeping the angle iron pressed outward will effectually secure the cap in position.

Having described and illustrated my invention, what I claim and desire to secure by patent is:—

1. In combination with a concrete fence post, having a vertically extending groove in one face thereof, a staple embedded in 70 the post at the lower end of the groove, a bar adapted to be inserted in the groove to hold the line wires therein, said bar having a pair of oppositely disposed notches extending into the edges thereof adjacent its upper and lower extremities, the notches in the lower part of said bar being adapted to engage the staple in the lower end of the groove, and a cap adapted to be inserted over the upper end of the post, said cap 75 having an inwardly projecting lug adapted to engage the notches in the upper end of the bar and thereby securely hold the bar in the said groove.

2. In combination with a concrete fence 85 post having a vertically extending groove in one face thereof, a staple embedded in the post at the lower end of the groove, a bar adapted to be inserted in the groove to hold the line wires therein, said bar having a 90 pair of oppositely disposed notches extending into the edges thereof adjacent its upper and lower extremities, the lower end of said bar being adapted to be inserted between the staple and the post, the notches 95 in the lower end thereby engaging said staple, and a hollow cap adapted to be inserted over the upper end of the post, said hollow cap having an inwardly projecting lug, the upper end of said bar being received within the hollow cap whereby the lug is adapted to engage the notches in the upper end of the bar and thereby securely hold the bar in the said groove.

3. In combination with a concrete fence 105 post having a vertically extending triangular shaped groove in one face thereof, a triangular shaped metal bar adapted to be in-

serted in said groove and provided adjacent its upper and lower extremities with a pair of oppositely disposed notches extending into the edges thereof, means at the 5 lower end of the groove for engaging the notches at the lower part of said bar, and means at the upper end of said groove for engaging the notches in the upper part of said bar, whereby said bar is securely held within the aforesaid groove.

JOHN S. MILLER.
